RAIL AND TIE FASTENING ASSEMBLY

Harry W. Frotzeller, Fairmont, Minn., assignor, by direct and mesne assignments, to Arthur Wm. Nelson, Park Ridge, Ill.

Application April 8, 1947, Serial No. 740,123

4 Claims. (Cl. 238—283)

1

This invention relates to improvements in rail and tie fastening assembly and it consists of the matters hereinafter described and more particularly pointed out in the appended claims.

One of the objects of the present invention is to provide a unitary assembly for use in fastening the rails of a railroad track to the ties thereof, and which provides a resilient track that will absorb shocks and jars at every tie upon which the assembly is used.

Another object of the invention is to provide an assembly of this kind, which is a self-contained unit that avoids the necessity of the usual spikes, hold-down clips and anchors now employed in a conventional railroad track.

A further object of the invention is to provide an assembly for the purpose mentioned, which reduces the noise of trains running upon a track in which the assembly is used and which affords a smoother and quieter ride therefor.

Also, it is an object of the invention to provide an assembly of this kind, which requires but a minimum of servicing in use and which may be accurately gauged and be quickly applied in track.

Again, it is an object of the invention to provide an assembly of this kind that includes parts which may be made from metallic plate stampings, which though light in weight, are strong and stiff and avoid the use of any parts requiring rolling in connection with special expensive rolls and whereby the cost is held at a minimum and production is facilitated.

The above-mentioned objects of the invention, as well as others, together with the several advantages thereof will more fully appear as the specification proceeds.

In the drawings:

Fig. 1 is a view in side elevation of the improved assembly when in use for its intended purpose with parts shown as broken away and in vertical section for a better illustration of the structure of the assembly.

Fig. 2 is a top plan view of the parts appearing in Fig. 1.

Fig. 3 is a view in end elevation of the improved assembly.

Fig. 4 is a top plan view of a certain resilient pad employed in the assembly on the scales of Figs. 1, 2 and 3.

Fig. 5 is a top plan view of a blank from which

2

the tie engageable plate of the assembly is made, said figure being on a scale less than that of Figs. 1, 2, 3 and 4.

Fig. 6 is a perspective view of one of a pair of certain angle bar elements employed in the assembly, said figure being substantially on the scale of Figs. 1, 2, 3 and 4.

In general the assembly is made up of certain metal parts, preferably produced from stamped 10 metallic plate, and a pad of resilient material such as natural rubber or synthetic rubber. The metal parts include a tie engageable plate and a rail engageable plate, which plates while spaced apart by the pad are preferably united to the 15 opposed surfaces thereof as by means of an adhesive, welding or other suitable means for uniting metal-to-rubber.

The tie engageable plate includes a body portion for seating engagement upon the tie and 20 includes integral downturned side parts that may be caused to enter the sides of the tie to hold the assembly thereto. This plate also includes integral upturned end parts which not only stiffen the plate but which may be used in connection 25 with a track gauging bar when the assembly is placed in track.

The rail engageable plate includes a body that forms a seat for the base of the rail and at each end thereof this plate carries an upright flange-like element providing shoulders for engagement 30 by the edges of the rail base. This plate also includes parts which may be bent inwardly about a vertical axis to engage and exert a hold-down action upon the upper inclined surfaces of both sides of the rail base.

The pad, before mentioned, is preferably made 35 from natural rubber or so-called synthetic rubber and is preferably adhesively united to both plates. It is provided with holes that open through the top and bottom surfaces of the pad 40 for the purpose of increasing the hysteresis loss, energy absorption and heat radiating qualities or characteristics thereof. The parts mentioned are secured together as a unitary assembly so as to be easily handled and installed in place and this without the necessity of the use of the conventional spikes or the like.

Referring now in detail to that embodiment of the invention illustrated in the drawings, the improved assembly includes a tie engageable member 10, a rail base engageable member 11,

and a resilient pad 12 between and fixed to the opposed surfaces of said members as will be later mentioned.

The member 10 is preferably made from a stamped metal plate blank appearing in Fig. 5. It is of a generally rectangular shape and is provided at the sides with flanges 13-13 and at the ends with flanges 14-14, the area 15 within said flanges and defined by dotted lines forming the substantially square body of the member 10 and which is of a width approximating the width of a conventional sawn railroad tie T. Each flange 13 is preferably wider at one end than it is at the other and the wide ends of said flanges are disposed at opposite ends of the blank. Thus the side edges of said flanges, while parallel with each other, are non-parallel with respect to the sides of the body. In the margins of these flanges are longitudinally spaced recesses 16-16 which alternate with intermediate tongues 17-17, end parts of which are bent over at a right angle to form sharpened tie entering lugs or claws 18-18, as best appears at the right hand side of Fig. 3.

In the forming of the blank, the flanges 13 are turned downwardly at an angle approximating 45° for further bending, and the end flanges 14 are turned upwardly to form the elements 19-19 which, while stiffening the member 10 as a whole in one direction, provides a shoulder for engagement by a track gauging device in applying the assembly to a tie T.

The rail base engageable plate 11 has the substantially square shape and stock of the body 15 of the member 10, but has a smaller area so that its edges are spaced inwardly from the edges of the body 15 of said member 10. When the rail, which is indicated at R, is relatively heavy per yard, say on the order of 131 lbs., and it is desired that such rail be canted inwardly, the greater part of the member 11 has a cant or inclination corresponding to that desired in the rail R and which cant is provided for by the sectional shape of the pad 12, later mentioned in more detail. Under such conditions the outer marginal end part 11a of the plate 11 is offset downwardly from the adjacent portion of said member and is preferably joined thereto by a somewhat ogee junction 11b, as best appears in Fig. 1.

At the outer and inner end of the member 11 there is operatively secured angle bar-like elements 20 and 21 respectively. The member 20 includes a horizontal flange 22 and an upright flange 23 and the member 21 includes similar flanges 24 and 25 respectively. The horizontal flanges are engaged upon and are spot welded to the end margins of the member 11, with the upright flanges 23 and 25 thereof spaced wide enough apart to receive between them the side edges of the base R¹ of the rail. The upper surface of each side of the base of the rail is conventionally inclined upwardly and inwardly, at opposite angles of about 14°, toward the web of the rail.

Each vertical flange 23-25 of the members 20 and 21 is formed with a slit 26 (see Fig. 6), which opens at one end through the ends of said flange and extend downwardly and inwardly thereof at an angle of 12° which approximates that of the upper surfaces of the rail base. These slits terminate at such elevation, above the bottom of the flange, as corresponds to the height of the side edges of the rail base. The end parts of the flanges 23-25 of said members, above the slits 26-26, provide tongues 27-27, which are bendable about a vertical axis coincident with the inner end of each slit. This bending of said

tongues, during application, may be carried out by means of a track maul, or other suitable tool.

The resilient pad 12, which is preferably made of an elastomer, such for example as so-called synthetic rubber or an admixture of natural and synthetic products, which will provide a pad having the desired resiliency, which will not readily oxidize, and which will not be adversely affected by oil, brine, and other elements, to which rail fastenings are frequently subjected, is of a generally square shape and is somewhat thicker than the plates 10 and 11. It has a bottom surface area approximating that of the body 15 of the member 10 and upon which it engages and has a top surface area approximating that of the member 11, which engages upon it. The side and end edges of the pad are bevelled as shown.

In the pad, rows of longitudinally and transversely extending, but spaced apart openings 28-28, are provided, each of which is in the shape of a Greek cross and which open at their top and bottom ends through the top and bottom surfaces of the pad. The upper surface of said pad is inclined from a bulge 29, near its outer end, the words "outer" and "inner" being used herein with respect to the position said ends are disposed when the assembly is in use in a railroad track. For use in assembly for lighter weight rails than those mentioned and wherein a cant is unnecessary, the top surface of the pad 12, as well as the member 11, will be flat and disposed parallel with the member 10.

The pad 12 may be secured to the plates 10 and 11 in different ways, but preferably an adhesive suitable for joining or uniting steel and rubber is used for this purpose.

When the assembly leaves its place of manufacture for its installation in a track, the pad 12 is disposed between and united to the plates 10 and 11. The flanges 13 of the plate 10 are disposed at substantially the angle appearing at the right hand side of Fig. 3 and the tongues 27-27 of the flanges 23 and 25 of the members 20 and 21 are in the straight unbent condition appearing in Fig. 6.

When assemblies of the kind mentioned are to replace the conventional tie plate and spikes in a railroad track the procedure is as follows:

After pulling spikes, the rail is removed to expose the tie plates which are then removed. The holes in the ties left by the pulling of the spikes are then plugged with wood pins and the tie surface is adzed off, preferably by machine, to present a uniform tie surface along adjacent ties. This is the same operation as now performed for relaying standard types of tie plates and new rails.

After a coating of preservative (such as a creosote preservative) has been applied to the adzed surface of the tie, one of the assemblies described herein is applied to the tie, with the member 10 engaged on the adzed surface, with the flanges 13-13 disposed at each side of the tie. At this time, the flanges 13-13 are in the angular position appearing at the right hand side of Fig. 3. This may be carried out with apparatus that will hold the member 10 of the assembly, the proper distance from the gauge of the opposite rail of the track and parallel with the same. The flanges 13-13 are then further bent downwardly as by the use of a track maul and this will cause the lugs 18-18 to enter the associated sides of the ties to be embedded therein so as to hold the assembly to the tie. In this respect it is pointed out that said lugs will enter the sides of the tie

at different elevations. Splitting of the tie is thus eliminated. Also, by arranging the lugs or claws 18 at each side of the tie at different and intersecting angles, a much better holding action is afforded.

If desired at this time, a spraying device may be used to spray a preservative coating around the plate 10 so as to seal any cracks that may be in the wood of the tie. This coating will also cover the top surface of the plate 11.

The rail R is then laid upon the assembly between the upright flanges 23 and 25 which at this time are straight. The side edges of the base of the rail will substantially abut against the inner surfaces of said flanges with the bottom surface of said base resting on the preservative coating on the upper surface of the plate 11 between said flanges.

With a maul or other suitable means, the end portions 27-27 of said flanges are bent inwardly toward the rail, the bending occurring about a vertical axis substantially coincident with the inner end of the slits 26-26. When bent inwardly at the angle appearing in Fig. 2, the bottom edges of said tongues will have a binding engagement with the upper surfaces of both sides of the rail base and impose a hold-down action thereon which locks the rail to the assembly. If desired, another preservative coating may be applied at this time.

As before explained, the pad 12 may be a synthetic rubber, as it is more resistant to the action of dripping brine and oil and the weather elements. However, the rubber should be of such character as to provide the desired deflection required under load and the permanent set thereof which should be preferably kept below 10% of its original height or thickness. It is preferred that the upturned flanges 19-19 extend across the width on the plate 10 because in addition to providing a more accurate gauging of the assembly, they also provide lateral strength across the tie as this reduces the tendency of the plate 10, which is relatively thin, to curve or bow across the top of the tie when being applied to the tie and also better resists distortion under the wave action of the rail.

The Greek cross shape of the openings 28 in the pad 12, which are closed at their ends by the plates 10 and 11 is provided for definite functional reasons. One important purpose of the resilient pad is to absorb shocks, vibrations and to a certain extent the wave action of the rail caused by the movement of a train on the rail. In order that the pad may properly absorb shocks, vibrations and the like, there must be a loss or dissipation of energy in the material of the pad itself. This action is somewhat in the nature of an "hysteresis" loss and can be increased by making possible a large overall distortion of the pad material. With the openings having the shape mentioned, a large amount of inside surface of the pad material is exposed so that a greater distortion of the material and much better heat radiation caused thereby are possible.

In general the "hysteresis" loss of a pad of the kind mentioned may approximate 10% of the applied energy. If the load applied is 15,000 lbs. and the deflection is a quarter of an inch, the total energy required to compress the pad is 1875 inch pounds or 156 foot pounds. If it is desired to absorb 10% of this to eliminate shocks, this absorption is 15 foot pounds per deflection.

Thus, if one hundred freight cars pass over

the assembly, there will be two depressions per car, one under each truck so that the total energy absorption in the pad material will be of the order of 3000 foot pound. This must be dissipated in the form of heat and the pad will radiate this heat through the surfaces of the openings to the engaged metallic surfaces and thence to atmosphere.

The improved assembly provides a more silent track, and one which provides not only better riding qualities therein, but one which is easier on the equipment of the trains.

Furthermore, the novel device is such that every assembly serves as a rail anchor resisting movement of the rail in both directions.

It will be understood that the energy absorption, and hence heat generation, occurs at the time a train is passing over the rail at the place where the improved assembly is located. The advancement of the train over the rail causes a very considerable movement of the air along the rail, which action assists in carrying away the heat generated by the train in its movement over the rail at that point.

While in describing the invention I have referred in detail to the form, arrangement and construction of the parts involved, the same is to be considered only in an illustrative sense so that I do not wish to be limited thereto except as may be specifically set forth in the appended claims.

I claim as my invention:

1. A rail and tie fastening embodying therein a tie engageable plate, a rail engageable plate, a pad of resilient material disposed between and united thereto, the tie engageable plate having parts at each side thereof that include lugs for entering the associated side of the tie for securing the plates thereto, means at the ends of said tie engageable plate for stiffening the same and providing shoulders for engagement by track gauging device, and means at the ends of the rail engageable plate including upstanding flange-like portions that are slit longitudinally to provide parts that are bendable inwardly about a vertical axis to have a hold-down engagement with the top surface of the base of the rail on said plate.

2. A rail and tie fastening device comprising a flat body plate adapted to rest upon a tie, said plate having portions adapted to be bent downwardly to form depending flange portions along opposite sides, said flange portions being of greater extent at one end than at the other, the margins of flanges being provided with spaced tongue portions and when the flange portions are downwardly disposed being adapted to be forced into the face of the tie at different elevations.

3. The arrangement defined in claim 2 in which the flange portion of minimum extent at one side is opposite the flange portion of maximum extent at the other.

4. A rail and tie fastening device comprising a flat body plate adapted to rest upon a tie, said plate having portions adapted to be bent downwardly to form depending flange portions along opposite sides, said flange portions being of greater extent at one end than at the other, the margins of flanges being provided with spaced tongue portions and when the flange portions are downwardly disposed being adapted to be forced into the face of the tie at different elevations, said plate also having marginal portions at opposite ends adapted to be bent upwardly to provide plate

stiffening flanges positioned to serve as track
gauging bar abutments.

HARRY W. PROTZELLER.
